UNITED STATES PATENT OFFICE.

SANFORD CLINE, OF HENRY, NORTH CAROLINA.

COLUMN-MILL.

1,249,332.

Specification of Letters Patent. Patented Dec. 11, 1917.

Application filed April 15, 1916. Serial No. 91,332.

To all whom it may concern:

Be it known that I, SANFORD CLINE, a citizen of the United States, residing at Henry, in the county of Catawba and State of North Carolina, have invented new and useful Improvements in Column-Mills, of which the following is a specification.

This invention relates to wood turning machines and more particularly to a mill for cutting and planing logs of rough timber and producing a finished column or article.

Objects of my invention are to provide an improved mill in which a rough unhewn log in the condition in which it is felled is adapted to be turned out as a complete and finished column having smooth and finished surfaces; to provide a device in which the bark, knots and other uneven or rough portions of the log are removed and the surfaces cut to a smooth and finished surface at a single operation, and this operation is accomplished in a short period of time and requires the attention of but one attendant or operator, so that the finished columns may be produced at a minimum cost. My improved mill may be used to produce a column which may be tapered to any desired extent, and it is adapted to receive a log of practically any size and trim the same down to a column of any diameter.

A further object of this invention is to provide an improved cutter and planer having means for removing the bark, knots, or the like, and also having means for planing the surfaces upon which it operates so that a rough unbarked log may be reduced to a finished column having a smooth and polished surface. My improved cutter is capable of operating at a relatively high rate of speed and at the same time does its work properly and neatly, so that a finished article may be turned out in a minimum space of time.

Referring to the drawings, wherein like numerals represent like parts in the several views,

Figure 1 is a top plan view of my entire device showing a log in position thereon.

Fig. 2 is a side elevation of my improved device, a portion of the cutter frame being broken away for purposes of clearness.

Fig. 3 is a sectional view taken on line 3—3, Fig. 1.

Fig. 4 is a sectional view taken on line 4—4, Fig. 1.

Fig. 5 is an elevational view of the cutting face of my improved cutter.

Fig. 6 is a sectional view taken on line 6—6, Fig. 5. 60

Fig. 7 is a fragmentary detail sectional view taken on line 7—7, Fig. 5.

Fig. 8 is a fragmentary detail sectional view taken on line 8—8, Fig. 5.

Fig. 9 is a detail view of the means for reversing the direction of travel of the carriage. 65

Fig. 10 is a detail fragmentary view of the cutter-head diagrammatically showing the relative positions of the teeth thereon. 70

10 designates a cutter-frame which may be of any suitable construction, and transversely of which is mounted a cutter-shaft 11 having fixedly mounted on one end thereof my improved cutter 12 hereinafter described more in detail. A main frame 13 mounted upon uprights 14, of any suitable height has along its longitudinal side-sills, beams or strips 15 which constitute a track-way on which the carriage carrying the work to be operated upon is adapted to reciprocate. 75

The carriage 16 on which the work to be operated upon is mounted, I have illustrated as comprising a horizontal table or frame having side sills 17 and end or transverse sills 18, the table or frame being mounted on suitable car wheels 19 engaging upon or guided by the trackway 15. The end sills, as clearly shown in Figs. 2 and 3, 85 are mounted upon and extend across the top of the side sills, and are provided with oppositely extending tongues or ribs 20. 21 designates a head-block or beam which extends longitudinally of the carriage 16 and 90 preferably protrudes beyond either end of the same as shown. The underside or surface of the head-block has brackets 22 provided with offset ends to form grooves 23 which receive the tongues 20 of the end sills 100 of the carriage, so that a tongue and groove arrangement is provided whereby the head-block may be guided transversely of the carriage, but the tongues fit loosely within the brackets, so that the block may be moved into a position at an angle to the longitudinal center line of the carriage when it is desired to taper the column. The head-block or beam carries at one of its ends, an upright or standard 24 having a work center, 105

herein shown as comprising a screw 25 suitably pointed at one end and adapted to be

rotated in a screw-threaded opening in the upper end of the standard 24 by means of a handle 26, it being understood that when the screw is rotated, the same is advanced forward or withdrawn from the log, thus permitting the same to be inserted in place or removed from its position upon the head-block. At the opposite end of the head-block is a pair of standards 27 spaced slightly apart and having bearings in their upper ends which rotatably receive the stem or spindle of a centering device 28, the latter having teeth or prongs 29 adapted to engage in the end of the log being operated upon, it being obvious that upon rotation of the centering device, the log will rotate therewith. Between the standards 27 and upon the spindle of the centering device 28 is a worm gear 30 meshing with the worm 31 mounted upon a spindle 32 which extends transversely of the head-block or beam, the same being rotatably mounted in bearing blocks 33. One end of the spindle 32 projects beyond the side of the head-block and carries a drum or pulley 34 about which passes a cable for turning the log to be cut, a handle 35 being provided for manually turning the log when the means for automatically turning the same is not required. Mounted upon the carriage 16 along the side of the head-block or beam 21 and extending parallel thereto is a guide-beam 36 pivoted adjacent one end as at 37 to the end sill of the carriage, so that the body portion of the guide beam may be swung laterally. The guide beam is mounted on or secured to the carriage by means of a tongue and groove connection similar to the tongue and groove arrangement between the head-block and the carriage. The guide beam 36 is connected to the head-block by means of a web comprising a pair of toggles 38, the opposite ends of the arms of which are connected to the head-block and guide-beam as at 39 and 40, respectively. A link or connecting bar 41 is connected at its opposite ends to the pin or pivot which secures the inner ends of the arms of the toggles together. By this arrangement, the guide beam and the head-block are always in parallelism with each other irrespective of the position of such members relative to the carriage, and thus when the guide-beam is swung about its pivotal point, the head-block is moved at an angle to the longitudinal center of the carriage, while, at the same time, the head-block may be moved bodily away from the guide-beam and yet retain its parallel position relative thereto. For moving the head-block laterally upon the carriage so that the log operated upon may be advanced toward or withdrawn from the cutter, I provide a segmental plate 42 secured as shown to the side sill of the carriage, and pivoted to the lower end of the

segmental plate is a lever 43 having a suitable dog 44 operated by means of a handle or finger-engaging lever 45, the dog being adapted to engage in suitable notches 46 for adjusting the head-block upon the carriage, suitable indicia being provided adjacent said notches. The head-block is connected to the lever 43 by means of a link 47, so that when the handle or lever 43 is swung about its pivotal point, the head-block is moved to or from the cutter depending on the size of the log desired to be cut, the tongue and groove arrangement 20 and 23 being such as to permit this relative movement.

Mounted also upon the side of the carriage and preferably adjacent the first segmental plate is a second segmental plate 42 having associated therewith members 43', 44', 45' and 46' which correspond to like members of the mechanism just described. The lever 43' is connected by means of a link 48 to the guide-beam 36 so that upon movement of the lever 43', the guide-beam is turned about its pivotal point 37 and due to the web arrangement between the guide-beam and the head-block, the latter is moved so that the log operated upon may be turned into a tapered column, and as the tongues or ribs 20 fit loosely within the grooves of the brackets 22, such movement is allowed for.

The means for driving the various mechanisms heretofore described may be of any desired form or construction, but preferably the rotation of the cutter, the reciprocating movement of the carriage which carries the work operated upon past the cutter, and the means for rotating the log operated upon, are effected from a single driven shaft which, in the present instance, comprises the cutter shaft 11. The cutter shaft has on its end opposite the cutter a fixed drive pulley 49 and a loose pulley 50 on the latter of which the belt which passes over a suitable motor (not shown) is adapted to be thrown when my improved mill is to be thrown out of operation. Mounted substantially below the cutter-shaft 11 and extending beneath the main or supporting frame 13 is a shaft 51 having on its outer end the pulley 52 about which passes a belt 53, the latter being driven by a small pulley 54 mounted upon the cutter arbor or shaft 11. The belt 53 is provided with a tightening pulley 80 mounted on a swinging arm 81 and having a pawl and ratchet as shown. Upon the opposite end of the shaft 51 is a grooved pulley 55, shown in dotted lines in Fig. 1, which receives thereabout an endless rope cable 56. The cable 56 passes from the grooved pulley 55 to an idle pulley 57 placed adjacent thereto, thence about the guide pulley 58 mounted in bearings on one end of the main frame 13 to and beneath an idle pulley 59 and over the drum or grooved pulley 34 and

mounted upon the spindle 32, and thence beneath a guide pulley 60, about a second guide-pulley 61 back to the grooved pulley 55. When the shaft 51 is rotated, the endless cable is moved, and through the drum 34 and the worm and gear mechanism 30 and 31 the log is rotated. When it is desired to rotate the cutter-head without revolving or moving the log operated upon the tightening 10 pulley 80 is withdrawn from the belt 53.

For the purpose of reciprocating the carriage so that the work or log operated upon may move longitudinally across the face of the cutter-head, I provide a shaft 62, Fig. 15 9 upon which is fixedly mounted a pair of belt pulleys 63, a loose or free pulley 64 adjacent each of the fixed pulleys and a grooved drum 65. One of the pulleys 63 is connected to a shaft 82 by means of a belt 20 66 and the other fixed pulley 63 receives a cross-belt 67 by means of which the pulley is driven through the rotation of the shaft 82, it being understood that any suitable belt-changing mechanism 68 for throwing 25 the belts on and off of the fixed pulley may be utilized to reverse the direction of travel of the carriage. The shaft 82 is driven from the shaft 11 by means of a belt 83 which may be provided with a belt-tightening device 30 similar to that designated by the numeral 80. A cable 69 passes about the drum 65 and stationary pulleys 70 positioned at opposite ends of the main supporting frame and is connected at its opposite ends to the 35 reciprocating carriage as shown.

In Letters Patent No. 864,612, granted to me August 27, 1907, I have shown and described an improved cutter-head having suitable cutter-blades and cutting edges, the 40 working face of the cutter-head being beveled outwardly, and while I have found the cutter-head described in this application to be admirably adapted for the purposes 45 therein set forth, I have made certain improvements thereover which adapts the cutter-head for use in my improved column mill. The cutter-head comprises a disk-like plate 71 having the working face thereof raised slightly at the hub or central portion, that is, the working face of 50 the cutter-head is beveled toward its periphery as at 85, and the cutting face is, furthermore, off-set adjacent its marginal edge as designated by 72 thereby providing an 55 annular face 86. Cutting knives 73 are located in slots 74 in the face 86 and preferably extend radially from the center of the cutter-head, and these finishing knives, which consist of relatively thin plates having 60 one edge beveled to provide a cutting edge, are retained in place in the slot by means of a chip breaker 75 and set-screws 76, the latter extending through screw-threaded openings in the body portion of 65 the cutter as shown in Fig. 6. By this

arrangement, the cutting knives may be easily adjusted and renewed, it being evident that to adjust the knives, it is merely necessary to turn the set-screws to relieve pressure against the chip-breaker, and 70 preferably, the knives are so set that their cutting edges protrude but a slight distance beyond the face of the cutter-head. I have found that when a very smooth finish is desired, the cutting edge of the knife 75 should extend but a hair's breadth beyond the chip-breaker, although, of course, when work of the highest quality is not demanded, it is not necessary to set the knife with such accuracy. By the use of my improved arrangement, I have found that a log of any kind of stock may be planed cross-grain or slash-grain. It will further be noted that the knives are set at an angle 80 to the plane of rotation of the cutter-head. 85 In the present instance, I have shown four finishing knives, but, of course, it is evident that the number of knives may be varied. The knives are provided with dust throats 77 which accommodate shavings or cuttings 90 and allow the same to be discharged from the cutter-head without interfering with the work.

For the purpose of removing the bark, 95 knots and other protuberances from the log, and to get the log in condition for the cutting knives just described to work thereon, I provide a number of teeth disposed in the annular face 86, and these teeth are arranged in a peculiar manner. Spaced equidistant apart and located angularly relative to the knives are pairs of teeth, and each pair of teeth consists in an inner tooth 78 and an outer tooth 79. The cutting points of the teeth extend beyond the face 86 of the cutter-head or plate 71, and are inclined therethrough in the direction in which the cutter head is adapted 100 to rotate as clearly shown in Fig. 2. The inner tooth 78 as shown in Figs. 6 and 10 is 105 adapted to be so adjusted that its cutting point is about on a straight line with the face 85 of the cutter-head. The outer teeth 79 are adapted to be so adjusted that their cutting points are in alinement with the 110 beveled face 85 and teeth 78, that is to say, they do not extend from the annular face 86 of the cutter-head as far as do the inner teeth 78 and it will be noted from Fig. 5 that the teeth 79 extend in a radial direction beyond the periphery of the cutter. 115 The teeth 78 and 79 are disposed in an extension 87 of the dust throat 77. Spaced between the pairs of teeth are single teeth 88 having dust-throats 89 and as shown in Fig. 10, the teeth 88 protrude from the face 86 to such an extent that the cutting points of the teeth 78, 79 and 88 are in alinement. The points of the single teeth 88 are at such 120 radial distance from the center of rotation 125

of the cutter-head that they operate on the work operated upon at a point between the lines on which the points of the teeth in pairs operate. The teeth are all similar in 5 form and preferably comprise pieces of rod of circular cross-section, the ends of the rods being sharpened or beveled to a point in the manner described. The teeth 78 and 79 have their beveled edges arranged in 10 one plane and the beveled edges of the single teeth arranged in a plane at right angles thereto, and by this arrangement, I have found that the uneven portions or irregularities on the surface of the work are 15 quickly and neatly removed. It is, of course, understood that the number of teeth may vary depending upon the stock operated upon and the quality of work which it is desired to turn out. The teeth are held 20 in place in the cutter-head by means of set-screws 90.

The cutting points of the teeth extend beyond the face of the cutter-head or plate 71 and are inclined therethrough in the direction 25 in which the cutter-head is adapted to rotate, as clearly shown in Fig. 2. The teeth preferably comprise pieces of rod of circular cross-section, the ends of the rods being sharpened or beveled to a point in the manner disclosed. In the present embodiment 30 of my invention, I have disclosed some of the teeth assembled in pairs, the pairs being spaced equal angular distances from each other. Located midway between the pairs 35 of teeth are single teeth, and the points of the single teeth are at such radial distance from the center of rotation of the cutter-head that they operate on the work operated upon at a point between the lines on which 40 the points of the teeth in pairs operate. It will be noted that the teeth which are arranged in pairs have their beveled edges arranged in one plane, and the beveled edges of the single teeth are arranged in a plane 45 at right angles thereto, and by this arrangement I have found that the uneven portions or irregularities on the surface of the work are quickly and neatly removed. The knives and teeth are provided with dust throats 50 to accommodate shavings or cuttings and allow the same to be discharged from the cutter-head without interfering with the work. The teeth 79 and 88 are held in place by screws 90.

55 The operation of my device will be readily understood from the foregoing description, it being understood that when the large drive pulley 49 is driven from any suitable source, the cutter-head is rotated, and by 60 means of the cables 66 and 56, the carriage which carries the log operated upon is moved longitudinally, so that the log is moved across the face of the cutter and, at the same time, the log is continuously rotated. The log may be advanced toward or

70 withdrawn from the cutter to produce any desired size of column by the lever mechanism described, and a tapered column may be obtained by swinging the guide-beam 36 at an angle relative to the longitudinal center of the carriage. The teeth of the cutter are so arranged as to remove bark, knots and other protuberances or irregularities on the surface of the log, so that the same is placed in condition for the finishing knives 75 to operate thereon. The finishing knives dress up the surface so that a smooth and finished article is produced. When it is desired to rotate the cutter head without rotating or moving the log longitudinally, the 80 tightening pulley 80 is withdrawn from the belt 53.

85 It will be seen that by my mechanism a rough unhewn log in the condition in which it is felled may be dressed and finished up 90 into a smooth round column, and the column may be of any suitable taper. If desired my improved column mill may be utilized to produce an octagon or other polygonal column, and this may be done by removing the rope cable 56 which rotates the log when producing a round column, so that the log is not rotated while the cutter is operating thereon. The carriage is moved longitudinally and the cutter operates on one portion 95 of the surface of the log producing a straight flat side. The handle 35 is then partially rotated to partially rotate the log through the worm gear mechanism, and then the carriage is again moved so that another straight 100 smooth side is produced upon the log, and this operation is continued until the column is finished.

105 It is, of course, obvious that my invention is susceptible of various modifications and mechanical changes which would be within the spirit of the invention without departing from the scope of the following claims.

What is claimed is:—

110 1. In a column mill, a carriage, a head-block upon the carriage rotatably supporting the log to be operated upon, a guide-beam upon the carriage, the head block being movable bodily laterally toward and from the guide beam though always maintained 115 parallel to said guide beam, in parallelism with said head-block for guiding the movements of said head block, means for maintaining the head-block and guide beam in parallelism with each other, means for swinging the guide beam about a pivot to move said head-block and log at an angle to the direction of travel of the carriage to produce a tapered column, and means for moving said carriage.

120 2. In a column mill, a carriage, a head-block on the carriage rotatably supporting a log to be operated upon, means for rotating the log, means for moving the carriage longitudinally, a cutter-head across the face of 130

which the log is adapted to be moved longitudinally, a guide beam upon said carriage connected to the head block and for guiding the movements of said head block and a web 5 comprising toggle mechanism for retaining said head-block and guide beam in parallelism with each other, the head block being movable bodily laterally toward and from the guide beam.

10 3. In a column mill, a carriage, a head-block upon the carriage rotatably supporting the log to be operated upon, a tongue and groove arrangement between the carriage and head-block permitting movement of the latter upon the carriage, a guide-beam pivotally connected to the carriage for guiding the movements of the head block, said head block being movable bodily laterally toward and from the guide beam, a web comprising 15 a pair of toggles the outer ends of the arms of which are connected to the head-block and guide beam respectively for retaining said head-block and guide-beam in parallelism with each other, means for moving said 20 head-block independently of the action of said guide beam, and means for swinging said guide-beam about a pivot to move said head-block therewith.

4. In a column mill a carriage, means on 25 the carriage for rotatably supporting a log, means for rotating the log, means for moving the carriage and log longitudinally, a guide beam connected to said means for rotatably supporting the log for guiding the 30 same, said last mentioned means being movable bodily laterally toward and from the guide beam though always maintained parallel to said guide beam, a cutter-head across the face of which said log is adapted to 35 move, and a common shaft for rotating the cutter-head and log and moving the carriage.

5. In a column mill a carriage, means on 40 the carriage for rotatably supporting a log, means for rotating the log, means for moving the carriage and log longitudinally, a 45 guide beam, toggles connecting said guide beam to the means for rotatably supporting

the log, and a cutter-head across the face of which the log is adapted to be moved. 50

6. In a column mill a carriage, means on the carriage for rotatably supporting a log, means for rotating the log, means for moving the carriage and log longitudinally, a 55 guide beam, toggles connecting said guide beam to the means for rotatably supporting the log, a pivoted hand lever, a link connecting said pivoted hand lever to the guide beam, and a cutter-head across the face of which said log is adapted to move. 60

7. In a column mill, a carriage, means on the carriage for rotatably supporting a log, means for rotating the log, means for moving the carriage and log longitudinally, a 65 guide beam, toggles connecting said guide beam to the means for rotatably supporting the log, a pivoted hand lever, means for holding said hand lever in any desired fixed position, a link connecting said pivoted hand lever to the guide beam, and a cutter head 70 across the face of which said log is adapted to move.

8. In a column mill, a carriage, means on the carriage for rotatably supporting a log, a pivoted hand lever, means for holding said 75 hand lever in any desired fixed position, a link connecting the hand lever directly to the means for rotatably supporting the log, means for rotating the log, means for moving the carriage and log longitudinally, a 80 guide beam, toggles connecting said guide beam to the means for rotatably supporting the log, a second pivoted hand lever, means for holding said hand lever in any desired fixed position, a link connecting said pivoted 85 hand lever to the guide beam, and a cutter-head across the face of which said log is adapted to move.

In testimony whereof I have hereunto set my hand in presence of two subscribing witnesses. 90

SANFORD CLINE.
